UNITED STATES PATENT OFFICE.

ALBERT ROTHROCK, OF JACKSON, MICHIGAN.

PRESSING AND IRONING BOARD AND STAND.

SPECIFICATION forming part of Letters Patent No. 601,481, dated March 29, 1898.

Application filed March 24, 1897. Serial No. 628,937. (No model.)

To all whom it may concern:

Be it known that I, ALBERT ROTHROCK, a citizen of the United States, residing at Jackson, in the county of Jackson and State of Michigan, have invented certain new and useful Improvements in Pressing and Ironing Boards and Stands, of which the following is a specification, reference being had therein to the accompanying drawings.

The invention consists in the construction of a pressing and ironing board and stand, and particularly in the construction of the pressing-board itself and the stand and the connection between the pressing-board and its stand, and, further, in the construction, arrangement, and combination of the various parts, all as more fully hereinafter described.

In the drawings, Figure 1 is a perspective view of my improved device. Fig. 2 is a broken perspective view showing the connection between the pressing-board and one of the standards. Fig. 3 is a broken vertical section through one of the standards, and Fig. 4 is a detached perspective view of one of the base-brackets and the end of one of the frame-sticks.

The device consists of a base, the standards, and the ironing-board, detachably secured to the standards. The base I preferably form of the two boards or strips A, connected together at the ends by the brackets B, which have the sockets C to receive the lower ends of the standards D, being detachably held thereto by means of the bolts a and the winged nuts b, the bolts engaging in the vertical slot c in the sockets of the base-brackets. These base-brackets are provided with the ears E, having the recess or journal-bearing F, in which journals G on the frame-sticks H engage, these frame-sticks carrying frames I, which are adapted to be folded up against the standards and also to stand at an angle thereto, and are preferably covered by a cloth or other covering J to form a continuous trough-shaped support beneath the pressing-board to keep the lower part of the garment which is being pressed from resting on the floor. These "frames" or "wings," as I call them, are connected together by cords K, passing through staples, and by pulling down on the cord centrally the wings may be closed up and held in their closed position

by engaging over a pin or hook M. One standard at the top is provided with a hinge O, which has a leaf extending over the top of the standard and the other leaf secured thereto. This leaf d, which extends over the top of the standard, is provided with a pin P. The ironing or press board Q is provided with an aperture at the end to engage this pin, so that it may be detachably supported on that standard, or when the end of the board is engaged with the pin a hinged connection is formed, the hinge being in the nature of a universal joint, so that without detaching the board from the standard, but simply lifting one end, a dress or other garment may be engaged upon the board and then the board replaced on the opposite standard. The opposite standard is provided simply with a stationary pin, such as P'.

The ironing-board Q has a straight under surface e, and the upper surface, which has the curved or inclined face i, rising to a point k, intermediate its ends and the oppositely-inclined face l on the other side of the point k, may be substantially an elbow-shaped projection on the upper face of this board. This elbow-shaped upper face with the long incline i and the short incline l enables me to lay snugly against the board any of the curved seams, such as the seam which unites the sleeve to the garment and other seams of a dress. By removing and reversing the board straight or flat seams may be pressed on the other face e.

I provide two sets of apertures m and n at right angles to each other at or near the ends of the board to engage with pins on the standards, so that I may use not only either edge, but also either side of the board, and the board is made wide enough, so that it may be used, if desired, as an ordinary ironing-board.

By making the standards detachable and the wings folding I am able to fold or pack the device in peculiar shape for storage or for carrying from place to place.

What I claim as my invention is—

1. The combination with the base and standards, of a hinge having one leaf secured to one standard and a projecting pin on the other leaf, a pressing-board provided with means engaging said pin to support the board

with either edge or side uppermost, and means on the other standard for supporting the pressing-board with either side or edge uppermost.

- 5 2. In a pressing-board, the combination of the base comprising the separated strips A, the metal end brackets secured to said strips and provided each with a vertical socket, standards detachably supported in said sockets, horizontal bearing-sockets formed on said brackets, a pressing-board supported at the tops of said standards, wings pivoted in said bearing-sockets, and means for holding the wings in adjustable positions, substantially as described.
- 10 3. In a pressing-board, the combination of

the base comprising the separated strips A, the metal end brackets B secured to said strips, the standards detachably supported in said brackets, the pressing-board detachably supported on the tops of the standards, the wings J pivoted in horizontal bearing-sockets formed in the brackets, and a cord connecting said wings and sliding in eyes on the standards.

In testimony whereof I affix my signature in presence of two witnesses.

ALBERT ROTHROCK.
